UNITED STATES PATENT OFFICE.

JOHN B. O'CONNOR, OF AURORA, ILLINOIS, ASSIGNOR TO LYON METALLIC MANUFACTURING COMPANY, OF AURORA, ILLINOIS, A CORPORATION OF ILLINOIS.

DOOR FOR SHELVING.

1,223,897.

Specification of Letters Patent. Patented Apr. 24, 1917.

Application filed August 25, 1915. Serial No. 47,263.

To all whom it may concern:

Be it known that I, JOHN B. O'CONNOR, a citizen of the United States, residing at Aurora, in the county of Kane and State of Illinois, have invented a certain new and useful Improvement in Doors for Shelving, of which the following is a specification.

My invention is particularly adapted to means for supporting the doors of shelving, lockers, and other structures which may be classed under the generic term "cabinets," and while the principle of the invention may be applied to structures of wood, it is especially intended and adapted for structures made of sheet metal. There are many situations where it is undesirable to employ the ordinary hinged doors which swing away from the structure, and, consequently, obstruct the passage in front of it, darken the interior of the structure and expose themselves to damage from trucks or other passing objects. Sliding doors, have, of course, been previously constructed but they lack the advantages resulting from my invention. As a result of my invention, the doors may be slid back to expose the entire front of any one of a number of compartments or units. Another result of my invention is that it becomes possible to securely lock both doors of a pair by manipulating a single key. Another result is that the locking of one pair of doors contributes to the securing of the adjacent pair. Other advantageous characteristics, which it is my object to obtain, will become apparent as the description proceeds, for example, as the result of my invention simple and efficient means of supporting the doors are obtained and the doors are prevented from binding when being slid from one position to another. These advantages result from the principles embodied in the structure illustrated in the accompanying drawings in which

Figure 1 is a front elevation of three sections or units of shelving embodying my invention, the interior shelves themselves being omitted for the sake of simplicity.

Fig. 2 is a plan view on the line 2—2, Fig. 1;

Fig. 3 is an enlarged view on the line 3—3, Fig. 4, showing the back of the doors;

Fig. 4 is a plan section on the line 4—4, Fig. 3;

Fig. 5 is an enlarged sectional elevation on the line 5—5, Fig. 3; 55

Fig. 6 is a detailed section on the line 6—6, Fig. 3;

Fig. 7 is a detail plan view on the line 7—7, Fig. 3;

Fig. 8 is a perspective of one of the brackets by which the track is supported, the location of such brackets being best indicated in Fig. 6; 60

Fig. 9 is a detail section on the line 9—9, Fig. 2, showing the supporting bracket of 65 Fig. 8 and some of the associated parts;

Fig. 10 is an enlarged detail in sectional elevation showing the guide rollers, track and associated parts;

Fig. 11 is a dropped sectional perspective 70 showing the lock, locking bar and associated parts;

Fig. 12 is a dropped sectional perspective showing one of the guides and a portion of 75 one of the sliding doors; and

Fig. 13 is a fragmentary section on the broken line 13—13, Fig. 1, showing the construction of a preferred kind of hand hold.

Similar numerals refer to similar parts 80 throughout the several views.

In the form of structure selected to illustrate the principle of the invention, the walls 1, back 2, top 3, and floor 4 may be taken as typical of any structure of this class. As in a well known type of shelving, the upright 85 walls or partitions 1 are braced back and front with uprights or face strips 5. Rigidly secured in a horizontal position near the top and near the bottom of the shelving, just behind the doors, are tracks 7 which are tubular, resembling hollow cylinders or pipes except that they have a horizontal slot 7^a at the back, as best shown in Figs. 9, 10, 11 and 12. This slot permits the entrance of an arm 8^a extending horizontally from each of a 90 number of brackets 8, the arm being provided at its end with a cylindrical head 8^b which fits rather snugly within the track and firmly supports it. The parts are so arranged and proportioned that when assembled the tracks 7 extend horizontally across the front of a number of units of the shelving slightly in front of the front edge of the face strips 5, as well shown in Fig. 10.

The upper track serves as a guide and 105 support for anti-friction rollers 10, these

rollers being preferably arranged in pairs near the ends of the doors, as illustrated in Fig. 3. One roller of each pair is above and the other below the track, and, consequently, 5 the door rides freely and yet securely upon the track. While the particular method of mounting the rollers may be varied, I prefer to mount them in sheet metal housings 11, shown on an enlarged scale in Fig. 10, the 10 housing having an outer surface 11^a which may be spot welded or otherwise secured to the back of the door and having two inwardly extending surfaces 11^b terminating in two opposed flanges 11^c. The axles 12 on 15 which the rollers are supported are themselves supported in the portions 11 and 11^c of the housings.

The doors of each section or compartment occur in pairs, and for convenience the 20 door 15 of each pair will be called the "internal" and the door 16 the "external" member of pair, the applicability of these terms being evident from an examination of Fig. 4 in connection with the other views of 25 the drawings. The door 15 has marginal flanges 15^a preferably along all four edges. This serves to stiffen the top and makes it practical to construct the door of a thinner gage of metal than would otherwise be employed. These flanges also serve to partially inclose the housings, as shown at the top of Fig. 10. They also serve to guide the doors at the bottom, the flanges being apertured to loosely receive the lower track 30 7. The latter feature will become apparent by referring to Fig. 12 where it will be seen that the flange 16^a of the door 16 has an aperture 16^b which receives the track and is extended to also accommodate the arms 8^a 35 of the supporting tracks 8. As shown, it is preferable to form channels at both the top and bottom of the external door and let them fit slidingly upon the upper and lower edges of the inner door. The channels thus 40 guide the external door upon the internal and the doors may be regarded as telescoping one into the other. By referring to Fig. 4 it will be seen that the vertical flange 16^b of the external door is wide enough to fit 45 over the corresponding flange of the companion door 15, and it will also be seen that the front of the door 16 slides in front of the door 15 and slightly overlaps the same when the doors are closed. In other words, the 50 external door of each pair is slightly wider than the space which it is intended to close thus overlapping the internal door to a slight extent. This insures proper guiding action and a more perfect closure. It is desirable to stiffen the overlapping edge of 55 the external door by a vertical beading 16^c.

Where a plurality of units or sections are employed the tracks 7 will ordinarily extend across the entire set thus avoiding 60 joints and the possibility of coming out of 65

alignment. In my construction, furthermore, the doors when used upon a plurality of units or sections are arranged alternately, each internal door being arranged between two external doors, and vice versa, as clearly 70 shown in Figs. 1 and 2. Consequently, it will be evident that when these doors are all unlocked and free to travel, the door at one end of the set may be slid back a distance equal to approximately a half of the 75 length of the entire structure. Therefore, it is possible for each door to be brought into register with or squarely in front of its mate and slid completely away from the section which it is intended to close. This 80 is a great advantage under many circumstances. For illustration, let it be supposed that my shelving is in use in the stock room of a factory where the various parts stored upon the shelves are not of sufficient value 85 to warrant their being kept in a burglar proof safe, but are of considerable value making it desirable that the shelving be locked up at night, or whenever the stock keeper is temporarily absent. By properly 90 manipulating the doors of shelving equipped with my invention, they may be slid so as to completely expose the entire width of any single section, and in fact in the case of a considerable number of compartments the doors 95 may be moved entirely away from those shelves or bins which contain the articles for which the stock keeper has most frequent calls. It will thus be evident that 100 shelving of my construction has the greatest flexibility and enables the user to completely expose the entire width of any single section and in some cases the entire width of a considerable number of sections. The doors may be stored opposite those sections 105 for which there is infrequent need of access. In any event when the doors are unlocked it is a simple matter to slide them upon their tracks, thus enabling the user 110 any moment to obtain free access to the entire width of any section.

I will now describe means which I have provided for locking the doors. According to my invention, I provide means for preventing the doors from sliding beyond the 115 end of the shelving taken as a whole. This is true whether the shelving consists of a single unit or a plurality of units. The means here illustrated consist of stops 20, clearly shown at the right end of Fig. 4 and 120 both ends of Figs. 1 and 2. These stops are secured by being bolted or otherwise fastened to the uprights 5 and are preferably hooked at the end so as to completely inclose the end of the door when locked. I 125 also provide means for preventing the doors of a pair from sliding relatively to each other. The means illustrated consist of a link work, one of the members whereof may be fastened by means of a lock or equivalent 130

device. In the preferred arrangement these parts are constructed, as best shown in Fig. 3, where it will be seen that a pair of links 21, 21 are permanently pivoted at the point 22 to the inside of one of the doors. The other end of this link is articulately connected to the free end of an arm 23 which forms one of the members of a bell crank pivoted at the point 24. The other arms 10 25 of these bell cranks are connected to each other by a link 26. Two parallel links 27 connect link 26 to a sliding locking bar 28. Said bar is arranged vertically and travels through a guide or keeper 29. Near the upper end of said locking bar, which is shown in perspective in Fig. 11, has an aperture 30 for receiving the end of a bolt 31 forming part of the lock 32. This lock is on the inside of the door but may be operated by 15 a key from the outside through the key hole 33. It will be evident when the bolt is retracted and the bar 28 is free to slide vertically in the guide 29, the two companion doors will be free to slide relatively to each other; but when the bolt is projected into 20 the bar and the bar is thus prevented from moving, it will prevent the link work from "working" and thus hold the doors locked in extended relation.

As the bell cranks are connected together 30 by the link 26 they must always rotate in unison and as they are also connected to the door 16 (by the links 21) at two different points it follows that the doors must travel 35 at the same rate at the top that they do at the bottom and hence cannot bind. In other words, the link work constitutes a parallel motion and renders the doors non-binding.

It is also clear that if there is a plurality 40 of pairs of doors and the doors are prevented from moving beyond the end of the shelving the doors will all be held against sliding when all of the pairs are held against movement of their individual parts relatively to each other; that is to say, no movement 45 of any of the doors can occur when the doors of each pair are locked relatively to each other.

To facilitate moving the doors, a hand 50 hold of some kind is provided, the form here illustrated consisting of sockets 35, as shown in Fig. 1, and in detail in Fig. 13.

In operation, when the doors are all extended and locked, no movement of any of 55 them can occur. By unlocking any pair of doors, all of the doors in the cabinet can be moved the length of a single door. In such case, limited access may be had to any one of the compartments or units. By unlocking 60 two pairs of doors, a compartment may be entirely exposed, provided, of course that the length of the compartment is no longer than the aggregate length of a pair of doors.

If all the doors are unlocked a wide choice 65 is offered to the operator as to which com-

partment he wishes opened, and if desired, a number of adjacent compartments may be completely exposed. In manipulating the doors, little care is necessary for they are not only supported upon roller bearings 70 but are provided with special mechanism which renders them non-binding.

In view of the foregoing, it will be seen that it is a simple matter to close and lock all of the doors and a simple matter to open 75 them to any extent desired. As the locking mechanism is, with the exception of the end stops 20, carried entirely upon the doors themselves, and as the tracks by which the doors are supported and guided may readily 80 be attached to existing shelving or other types of cabinet, it is a simple matter to equip existing structures with doors embodying my invention. When the doors are in place, the supporting means are invisible 85 from the outside, especially when the doors are closed. Thus I avoid the use of external tracks, hinges and other projections which detract from the appearance of a structure and are frequently in the way.

Having thus described my invention, what I claim as new and desire to secure by Letters Patent, is:—

1. A cabinet having a track extending across the front, and a pair of doors slidable 90 upon said track, one door of the pair having flanges fitting over the top and bottom edges of the other door to be guided thereby.

2. A cabinet having a track extending across the front, and a pair of doors slidable 100 upon said track, one door having anti-friction rollers near each end traveling upon said track and the other door having anti-friction rollers near one end traveling upon said track, the other end of the last mentioned door being flanged to fit over the upper and lower edges of the other door to be guided thereby.

3. A cabinet having a plurality of compartments arranged side by side, a track 110 extending across the front of said compartments, and a set of doors for each compartment, the doors sliding upon said track, the doors of a set telescoping with each other whereby they may be brought approximately 115 into register, the track being continuous across the front of the cabinet whereby the telescoped doors may be slid far enough to completely uncover a compartment.

4. A cabinet having a plurality of compartments arranged side by side, a pair of doors for each compartment, the doors of a pair telescoping with each other and the aggregate length of the pair of doors being approximately equal to the length of the 125 cabinet, and a track upon which said doors are slidable to cover and uncover said compartments, said track being continuous across a plurality of compartments to thereby permit the doors of one compartment to 130

- slide over to a point in front of another compartment to thereby completely expose the first compartment.
5. A cabinet having a track at the front, and a pair of telescoping doors traveling upon said track, the external door having a channel at the end remote from the internal door whereby, when the doors are brought into register, the channeled end of the external door will fit over the inclosed end of the internal door to thereby prevent the external door from swinging away from the plane of the internal door.
6. A cabinet having a track at the front, and an internal and an external door constituting a pair of doors traveling upon said track, the external door having a channel top and bottom fitting over the top and bottom edge of the internal door and the external door also having a vertical channel at the end remote from the internal door, the vertical channel fitting over the end of the internal door, whereby, when the doors are in register, the external door will engage the internal door at the top, bottom, and end.
7. In combination, a cabinet having a track extending across the front, a door traveling upon said track, a second door supported at one end upon said track and at the other end upon the first mentioned door, and means for keeping said doors parallel as they travel relatively to each other.
8. In combination, a cabinet having a track extending across the front, a pair of doors traveling upon said track, and a link-work connecting said doors whereby when the elements of the link-work are locked relatively to each other the doors are prevented from moving relatively to each other, said doors telescoping with each other, whereby one door forms a guide for the other.
9. A cabinet having a track extending across the front, a pair of doors traveling upon said track, two bell cranks fastened to one of said doors, and a link connecting said bell cranks to make them rotate in unison, said bell cranks also being link connected to the second door of the pair, said doors telescopically interfitting with each other, whereby one door forms a guide for the other.
10. In combination, a cabinet having a track at the front, a pair of telescoping doors slideable lengthwise of said track, a link work for compelling said doors to maintain parallel relation to each other during relative travel, and means for locking said link work against working.
11. In combination, a cabinet having a track at the front, a pair of telescoping doors slideable lengthwise of said track, a link work for compelling said doors to maintain parallel relation to each other dur-
- ing relative travel, and a lock mounted on one of said doors for preventing relative movement of the members of the link work.
12. In combination, a cabinet having a pair of telescoping doors, means for slidably supporting said doors, a link work for compelling the doors to maintain themselves parallel to each other during their relative movement, and a lock for holding one of the members of the link work against movement when the doors are extended.
13. In combination, a cabinet having a pair of doors movable relatively to each other, a track whereon said doors are slideable, a pair of bell cranks on one of said doors, means for compelling said bell cranks to rotate in unison, a pair of links connecting said bell cranks individually to the second door of the pair for compelling parallel travel of the doors, a locking bar operated by said link work, and a lock mounted on one of the doors and having a bolt adapted to engage said locking bar when in the position to which it is brought by the link work when the doors are extended.
14. In combination, a structure of the class described having a track arranged in front, a pair of doors slideable relatively to each other lengthwise of the track, a pair of bell cranks mounted on one of said doors, a link connecting said bell cranks for compelling them to rotate in unison, links individually connecting said bell cranks to the other door, a locking bar operated by said bell cranks and mounted on the same door as the bell cranks, and a lock also mounted on the same door as the bell cranks for locking said bar and thereby preventing movement of the doors relatively to each other.
15. A structure of the class described having a plurality of compartments arranged side by side, a track extending entirely across the structure at the front thereof, a plurality of pairs of doors, slideable upon said track, the aggregate length of the doors being equal to the total length of the structure, one door of each pair being internal and the other external in the sense that the external door is guided by the internal door and is capable of being brought approximately into register therewith, stops at the ends of the structure for preventing the doors from traveling beyond the end of the structure, and means on each pair of doors for locking said doors in extended relation.
16. A structure of the class described having a plurality of compartments arranged side by side, a track extending entirely across the structure at the front thereof, a plurality of pairs of doors, slideable upon said track, the aggregate length of the doors being equal to the total length of the structure, one door being entirely supported upon

the track and the other door of the pair sliding upon the other whereby the two doors of a pair may be brought approximately one directly in front of the other, stops at the ends of the structure for preventing the door from traveling beyond the end thereof, a link work upon each pair of doors con-

necting the doors together in pairs, and means for preventing movement of the parts of the link work relatively to each other.

In witness whereof, I have hereunto subscribed my name.

JOHN B. O'CONNOR.
